DOUBLE THREADING CLIP

Stanley H. Sather, New Westminster, British Columbia, Canada, assignor to Aktiebolaget Svenska-Flaktfabriken, Stockholm, Sweden

Filed Mar. 23, 1965, Ser. No. 442,004

12 Claims. (Cl. 24—253)

My invention relates to a double threading clip, used particularly in pulp mills, for threading wet or dry material into processing machines. Such material is normally 10 a web. Single threading clips are well known in the art; my double threading clip is used in the same manner as a single clip.

A double threading clip is claimed in the copending application of Alphons Livio Rosengqvist filed August 28, 1964, under Serial Number 392,798, and therefore my disclosure herein is confined to the structure of my invention, to a novel method of continuous winding of a multiple spring element thereof, and to a novel method of winding a discrete unit, a plurality of which form an alternative spring embodiment.

Single threading clips are adapted to grasp one side of the web. This places an unequal pull upon said web, a disadvantage which is generally recognized in the industry.

An obvious solution appears to be a double clip, which could overcome this disadvantage above by grasping both sides of the web at once. Heretofore, attempts to provide double clips have not been entirely successful and, accordingly, at the present time, single clips are in general use both in European and North American mills, and elsewhere.

One difficulty has been to provide a double clip having a base portion with the required strength and flexibility.

My clip includes a body having a base, integral with the body foldable flap elements on each side of the base, the flap portions about half the width of the base portion and strongly urged against said base by spring means. In this way grip is effected upon both sides of the web.

It will be understood that, pulling from a central strap of such a clip, stresses are introduced tending to cause the base to collapse—which difficulty is encountered in previous attempts to provide a practical double clip.

In one way I provide the necessary strength and rigidity maintaining the required flexibility, by transverse spring elements integral with the spring means used to urge the flaps against the base, the multiple spring formed from a continuous length of spring wire.

An alternative spring means having such strength, rigidity, and flexibility is provided by a multiple spring assembled from a plurality of discrete units, each unit having transverse members. In such a discrete unit multiple spring assembly, contiguous transverse elements of adjoining units are secured together thus giving greater transverse strength which, in some cases, may be an advantage.

Another advantage of the discrete unit construction is that a stock of such units may be prefabricated, thus spring elements for threading clips of different lengths may be assembled at will. Further, the discrete units themselves are well adapted to be produced by comparatively simple automatic winding machinery.

An important object of my invention is to provide a such spring either continuously formed, or assembled from discrete units, the multiple spring having transverse elements cooperating with helical spring elements and generally triangular loop elements, by means of which cooperation the necessary gripping closure is effected, said transverse elements suitably reinforcing the base.

A further important object is to provide a quick, cheap and simple method of winding a multiple spring of and from a continuous length of spring wire.

2

Still further important objects are to provide a such spring assembled from a plurality of discrete elements, and to provide a quick and simple method of winding a said discrete element.

5 Other objects and advantages of my invention, the construction thereof, and the spring winding methods, will be apparent to those skilled in the art from the following detail description and drawings.

FIG. 1 is a plan view of a clip according to the present invention.

FIG. 2 shows the clip as it would appear in plan with the foldable flaps fully open,

FIG. 3 is a section on line 3—3 of FIG. 1, and is diagrammatic,

FIG. 4 shows one embodiment of the multiple spring, and is illustrative of the method of continuous winding,

FIG. 4A is a cable clamp, in perspective at enlarged scale,

FIG. 5 is a discrete unit of an alternative multiple spring embodiment, and

FIG. 6 is a multiple spring assembled from a number of discrete units as FIG. 5.

In the drawings, the springs are shown diagrammatically.

25 Referring to FIGURES 1, 2, and 3, the threading clip indicated generally by the numeral 10 has a double envelope body portion 11, and integral therewith the generally triangular part 12 extending outwardly from 11. Securely stitched to the outer apex 13 of member 12 is the strap or belt member 14, suitably strong burlap, which strap also is secured to a cable, as later explained.

As best seen in FIGURE 3, the double envelope 11 of strong canvas or like material, has a base 15, the triangular part aforesaid, and the foldable flaps 16 and 17. As seen in FIGURE 2, the flap 16 folds along the broken line 16A, and the flap 17 along the broken line 17A, to assume the positions shown in FIGURES 1 and 3. Side edges of the base portion are defined by said broken lines.

FIGURE 3 is diagrammatic, dimensions at right angles to the plane of FIGURE 1 being exaggerated. The body 11 is double having an inner layer 18 and an outer layer 19. Between these two layers is secured a multiple spring indicated by the numeral 20, serving to urge the foldable flaps 16, 17 to the closed position, FIGURE 3. The multiple spring 20 may be the continuous embodiment FIGURE 4, or the discrete unit assembly shown in FIGURE 6.

40 FIGURE 2 shows the clip with the flaps 16, 17 fully open better to illustrate the construction. In use, the flaps are opened only to about 90° to permit insertion of the web to be grasped, say to the extent shown in FIGURE 3 by the broken lines 21. It will be understood that, as the flaps 16, 17 are strongly urged to the closed position, FIGURE 1, by the multiple spring member, force is required to hold them in such broken line position.

45 The multiple spring is an important element of my invention. The construction of one embodiment, and a method of winding it from a continuous length of spring wire stock, are described below with particular reference to FIGURE 4.

50 In FIGURE 4 only, the numeral 22 indicates generally a such multiple spring, having two aligned rows 23 of helical elements designated 24.1, 24.2 etc., transverse elements designated 25.1, 25.2 etc. extending between the two aligned rows as shown, and generally triangular loop elements designated 26.1, 26.2 etc., each triangular element having an apex A adjacent the helical elements aforesaid, and a base B outwardly disposed substantially parallel to the rows 23.

55 A preferred method of winding a such multiple spring includes the following steps, the winding is carried out from a continuous length of steel spring wire from a

spool obviously supported by means, not shown, to permit any required length of wire to be drawn from the spool. In the description, the terms "clockwise" and "counter clockwise" refer to "clockwise" and "counter-clockwise" springs as indicated by the directional arrows in FIGURE 4, and as viewed from the right hand side of the figure. This is not necessarily the direction of winding on a mandrel to produce the required spring.

Method I

(1) Upon a suitable mandrel wind a first clockwise helical element 24.1. The diameter of the helix, the number of turns, and the diameter of the spring wire are determined from ordinary design procedures. Sixteen turns of Number 14 American Wire Gage (AWG) wire wound upon a $\frac{7}{64}$ inch diameter mandrel is satisfactory.

(2) Remove the first helix from the mandrel and wind the second clockwise helical unit separated from 24.1 by the length of the transverse element 25.1, the second unit to lie on a side of 25.1 opposite to that upon which the first said helical unit is formed. There have now been produced, the first helical element 24.1, the transverse element 25.1, and the second helical element 24.2, the axes of the two helical elements being substantially parallel and separated by the said transverse element, and upon opposite sides thereof.

(3) Using a suitable jig, form a triangular loop element 26.1 adjacent the second helical element 24.2, having a base B disposed outwards and an apex A disposed inwards adjacent the helix 24.2. Secure the loop with a clamp 27 at the apex A. The axes of the helical elements, the transverse element 25.1, and the triangular element 26.1, are substantially coplanar as formed.

(4) Next wind a third counter clockwise helical element 24.3 coaxial with 24.2, and closely adjacent to the apex A of 26.1.

(5) Form a second transverse element 25.2 extending to the end of 25.1 adjacent the first helical element 24.1, and secure the first and second transverse elements to one another adjacent 24.1, by affixing a cable clamp 27 as shown.

(6) Wind the counter clockwise helix 24.4, aligned with 24.1.

(7) Form the second loop element 26.2 in the manner indicated in step (3), adjacent the helical element 24.4.

(8) Repeat steps (1) to (5) until the required length of multiple spring is attained.

(9) Upon completion of step (8), a helix is required to complete the row of helices of which 24.1 is the first element; wind a final counter clockwise helical element 24-L-1 to complete this row.

(10) Extend the wire to the second helical row to form the last transverse element 25L and secure this by a clamp 27 to the adjacent transverse element.

(11) Finish off with the final helical element 24-L-2 of the second row, which element is clockwise, and cut the wire off at the end of 24-L-2 thus completing the multiple spring.

The clamps referred to herein are common cable clamps obtainable commercially in a number of styles and sizes. A clamp such as that shown at enlarged scale in FIGURE 4A is suitable. This is a metal clamp adapted to be secured by crimping.

The foregoing steps will have provided a multiple spring 22, with two aligned rows of helical elements separated by transverse elements and having outwardly extending triangular elements with their bases parallel to the helical axes and of such length as may be required.

It is to be understood that the length of the rows of helical springs is according to the length of the foldable flaps 16, 17; that the separation of the helical rows, and thus the length of the transverse elements, is according to the width of the base 15 of the body of the clip, see FIGURES 1 and 2, and that the size of the

triangular loop elements is according to the width of the foldable flaps 16, 17.

The cable 28 FIGURE 4 extends through the first row of helical springs, thence outwardly around the periphery of the triangular portion 12 of the clip base, as shown in FIGURES 1 and 2, through the second helical row. Suitable cable diameter is $\frac{3}{32}$ inch—that is, about 0.10 inch. A suitable length of such cable is inserted through the helices as above, and secured at each end by the clamp means 27A, FIGURE 4. As seen in FIGURES 1 and 2, the cable is secured to the strap 14 to which the load is applied. To prevent the cable being pulled out of the helices as the load is applied in use, the clamps 27A should be brazed or soldered to the cable. Crimping is however adequate to secure the other clamps.

The $\frac{7}{64}$ inch diameter mandrel gives to the helices wound of No. 14 wire an inside diameter such that the $\frac{3}{32}$ cable may readily be inserted. It will be understood that the diameter of the wire and of the mandrel, cable diameter, and the number of turns in each helix, as given are by way of example only, and are capable of variation.

According to the requirement, the number of turns of the helices may be from about 10 to about 20, the wire may be, say No. 12 AWG, or as small as No. 16 AWG, and the mandrel diameter may be between 0.06 and 0.25 inch. It is not essential that all the helices of a row have the same number of turns.

In making the completed clips, I prefer to make the multiple spring first.

As shown in FIGURE 4, the multiple spring 22 is untensioned. Tensioning is effected by rotating the lefthand triangular elements clockwise through $180+^\circ$, and the right hand triangular elements counter clockwise to the same extent.

I prefer to fabricate my threading clip by placing the tensioned spring, held tensioned by suitable jig means, upon the outer canvas layer 19, previously cut to size, then assembling the inner canvas layer 18 thereto, the tensioned triangular elements therebetween. Suitable fabricating procedure will readily be apparent to those skilled in the art; therefore I shall not describe that procedure in detail. It is however to be understood that the multiple spring must be strongly fastened, by stitching and/or other means, to the canvas structure and I prefer to use a latex or similar adhesive supplementary to stitching. The strap 14 is strongly secured to the cable 27 by looping and stitching, or by other suitable means. Plastic dabs 29 are applied, as is common practice, to the outer canvas over the position of the several clamp means 27 to prevent wear. Friction pads 30 are also provided, according to common practice, better to grip the web.

In certain circumstances it is desirable to provide additional strength in the transverse members of the multiple spring. I accomplish this in one way by making up the spring from discrete units as illustrated in FIGURE 5 and designated generally by the numeral 31.

A method of winding a such unit to provide the required structure is described as follows, referring to FIGURE 5. Spring wire diameter and mandrel diameter are as before stated with reference to Method I, and "clockwise" and "counter clockwise" have the before-stated meanings.

Method II

(1) A short distance from the free end of the wire stock, as indicated by the broken line 32', wind a first short clockwise helix 32, of two or three turns, cut off the portion 32'.

(2) Now wind a clockwise helical spring 24A1 as before described with reference to springs 24 of Method I. This helix is wound at a distance from helix 32 equal to the length of a transverse member 25A1.

(3) Next form the triangular loop 26A as described in step (3) of Method I securing the apex A by a clamp 27.

(4) Now wind a counter clockwise helix 24A2 coaxial with 24A1.

(5) At a distance from 24A2 equal to the length of the transverse element 25A2 wind a second short counter clockwise helix 31, of two or three turns. Cut the wire 5 stock at the end of helix 33.

(6) Fasten the two transverse elements by a clamp 27 placed close to the short helices 32, 33.

This completes a discrete unit. It is to be understood that the various elements are, as before, coplanar.

A number of discrete units 31 may readily be assembled to a cable 28 to form a discrete unit multiple spring having the general configuration of the FIGURE 4 spring, but differing therefrom in that the transverse elements are duplicated. A such discrete unit assembly is illustrated diagrammatically in FIGURE 6.

One end of the cable 28 is passed through the helices 24A1 and 24A2 of the first unit designated 31-A, and the other end is passed through the first and second short helices 32 and 33 thereof. The cable is now passed through helices of the second unit 31B, which second unit is so placed that the triangular elements 26A and 26B of the first and second units are disposed outwards as shown. The now adjacent transverse elements of the first and second units are secured together by one or more clamp means 27.

Additional units are added in the same manner until an assembly of the required length is obtained. When the ends of the cable passing through the helices of the last unit are secured by the clamp means 27A', corresponding to and for the same purposes as clamps 27A, FIGURE 4, the clamps 27A', should be soldered or brazed to the cable as before. In the FIGURE 6 discrete unit multiple, the short helices of a number of intermediate units may be soldered or brazed to the cable additionally to secure the cable to the spring.

The discrete unit multiple spring embodiment is assembled as previously described.

In Methods I and II it is specified that the first helix be clockwise. The first helix may be counterclockwise, but, if this were done, all the remaining springs would be changed also, i.e., clockwise where contra is stated, and vice versa.

When the sequence of direction outlined in the methods is followed (or the reverse sequence) the triangular and transverse elements will lie flat against the base and flaps. If the relative sequence is not followed, the resultant multiple spring will still be operable but the triangular apices and the points of junction of the transverse elements will (or may, depending upon what particular sequence is followed) be separated by a distance equal to the diameter of the helices. Accordingly, I prefer to use the sequences indicated, or the reverse thereof.

It is to be taken that the foregoing disclosure and detailed description is not intended in a limiting sense, but is by way of example, and that modified and alternative embodiments may readily be made within the scope of the present disclosure.

The embodiments of the invention in which an exclusive property or privilege is claimed are defined as follows:

1. In a double threading clip for leading a web through a processing apparatus, said clip including a body of flexible material including a base portion and flap members foldable thereagainst with spring means in said body 65 to urge said flaps against said base,

the improvement wherein said spring means comprises a multiple spring including first and second aligned rows of helical spring elements, the rows being disposed along opposite side edges of the base and being 70 in spaced, parallel relationship with one another; said springs comprising discrete units each including (a) transverse elements; (b) two rows of helical members joined by said transverse elements; (c) an outwardly extending element intermediate adjoining 75

helical elements in at least one of said rows; (d) ends on said transverse members, intermediate adjoining helical elements in the other of said rows and (e) means to fasten the transverse members together near said ends, and means to fasten a discrete unit to an adjoining discrete unit to form said multiple spring.

2. In a double threading clip a multiple spring for closing said clip onto a web comprising a first row of aligned helical spring elements, a second row of aligned helical spring elements, transverse elements extending from between the helical elements of the first row to between the helical elements of the second row, and holding elements extending outwards of each row of helical spring elements from between the elements of each row and cooperable with said transverse elements to effect closing of said clip.

3. A multiple spring means as claimed in claim 2, wherein the said spring is formed from a continuous length of spring wire.

4. A spring means as claimed in claim 2 wherein said spring is formed of a plurality of discrete units; each such unit including two rows of helical spring elements, transverse elements joining the two rows of helical elements, an outwardly extending element within at least one of said rows, the transverse members having ends within the other of said rows, and means to fasten the transverse members together near said ends; and means to fasten together adjoining discrete units of the multiple spring with the said one row of one unit in alignment with the said other row of the adjoining unit.

5. A spring means as claimed in claim 4 wherein the fastening means secures the contiguous transverse members of adjoining units to one another.

6. A spring means as claimed in claim 4 including a length of flexible cable extending axially through the first said row of helical springs; thence in an opposite direction through the second said row; fastening means at each end of the cable to secure the same against withdrawal from the said rows; the length of the cable being such as to provide a slack portion between the rows; the slack portion adapted for attachment to a strap of a double threading clip, the ends of the transverse members being attached to said cable.

7. A spring means as claimed in claim 6 wherein the attachment comprises a short helix of two or three turns in said other row for the passage of the cable therethrough.

8. A spring means as claimed in claim 2 including a length of flexible cable extending axially through the first said row of helical springs thence in opposite direction 50 through the second said row; fastening means at each end of the cable to secure the same against withdrawal from the said rows; the length of the cable being such as to provide a slack portion between the rows, the slack portion adapted for attachment to a strap of said double threading clip.

9. The method of winding a multiple spring for a double threading clip, using a continuous length of spring wire comprising the steps of:

- (1) winding a first helical element in one direction;
- (2) similarly winding a second helical element in the one direction separated from the first helical element by the length of a transverse element, the helical elements being parallel and extending in opposite directions from the transverse element;
- (3) forming a first generally triangular element having an apex at the end of the second helical element, and a base parallel to the helical elements, said base at the side of the second helical element remote from the first helical element, and coplanar with the helices, and securing sides of the triangular element to one another near said apex;
- (4) winding a helical element in the opposite direction constituting a third helical element, the third said element being coaxial with the second said element, thus providing two elements of a first row of

- helical elements, the apex of the first triangular element being disposed between said second and third helical elements;
- (5) forming a second transverse element by extending the wire from the third helical element to the end of the first transverse element adjacent the first helical element, and securing the transverse elements to one another adjacent said first helical element;
- (6) winding a fourth helical element in the opposite direction coaxial with the first said helical element, thus providing two elements of a second aligned row of helical elements;
- (7) forming a second triangular element thus providing a second triangular element extending outwards of the second said row of helical elements, and coplanar with the transverse elements;
- (8) severing the continuous length of spring wire after the required length is obtained.

10. The method as claimed in claim 9 using steel spring wire having an American Wire Gage number between the limits No. 12 and No. 16, and winding helices having between 10 and 20 turns, using a mandrel having a diameter between 0.06 and 0.25 inch.

11. The method of winding a discrete unit of a multiple spring for a double threading clip, comprising the steps of:

- (1) at a short distance from the free end of a reel of spring wire, winding two or three turns in one direction, said two or three turns having an axis;
- (2) at a distance from the said turns equal to the length of a transverse member, winding a first helical element in said one direction, coplanar with and parallel to the aforesaid axis of the two or three turns, the first helical element disposed substantially at right angles to the transverse element and extending from

5

10

15

20

25

30

a side thereof in a direction opposite to that of the two or three turns aforesaid;

- (3) forming a triangular element having an apex adjacent the first helical element, and a base parallel thereto, the base disposed outwards, the triangular element coplanar with the transverse element, and securing sides of the triangular element to one another near said apex;
- (4) winding a helical element in the opposite direction, being a second such element, coaxial with the first helical element;
- (5) extending the spring wire to the turns thus formed to form a second transverse member, winding a second two or three turns in the opposite direction coaxial with the first said turns, cutting the wire stock and securing the first and second transverse elements together adjacent said turns.

12. The method as claimed in claim 11 using steel spring wire having an American Wire Gage number between the limits No. 12 and No. 16, and winding helices having between 10 and 20 turns, using a mandrel having a diameter between 0.06 and 0.25 inch.
